UNITED STATES PATENT OFFICE.

LLOYD JOHNSON, OF UHRICHSVILLE, OHIO.

TORPEDO GUARD-NET.

1,249,107.

Specification of Letters Patent.

Patented Dec. 4, 1917.

Application filed July 6, 1917. Serial No. 178,982.

To all whom it may concern:

Be it known that I, LLOYD JOHNSON, a citizen of the United States, residing at Uhrichsville, in the county of Tuscarawas 5 and State of Ohio, have invented certain new and useful Improvements in Torpedo Guard-Nets, of which the following is a specification.

This invention relates to apparatus adapted to be associated with boats of various kinds to protect their hulls from torpedoes, and has for one of its objects to provide an apparatus including floats or buoys connected to the boat and movable therewith 15 through the water, the floats or buoys supporting a guard net which will intercept torpedoes or like missiles and either prevent them from reaching the hull of the vessel or explode them upon contact with the net 20 and a sufficient distance from the vessel to prevent the concussion from being communicated thereto.

Another object of the invention is to provide an apparatus of this character having 25 guiding or steering attachments whereby the apparatus is maintained at a uniform distance from the hull of the vessel.

Another object of the invention is to provide a device of this character which may 30 be elevated for storage upon the deck of the vessel when not in use, and which may be quickly located in position when required.

With these and other objects in view, the invention consists in certain novel features 35 of construction, as hereinafter shown and described and then specifically pointed out in the claims; and in the drawings illustrative of the preferred embodiment of the invention—

40 Figure 1 is a diagrammatic plan view of the hull of a vessel with the improved guard device in position relative thereto;

Fig. 2 is a side elevation of the parts shown in Fig. 1;

45 Fig. 3 is an enlarged plan view of one of the float devices;

Fig. 4 is a side elevation of the parts shown in Fig. 3;

50 Fig. 5 is a transverse section on the line 5—5 of Fig. 3.

Corresponding and like parts are referred to in the following description and indicated in all the views of the drawings by the same reference characters.

55 The improved device comprises primarily a guard net of sufficient strength to resist or

check the impact of torpedoes and suspended at a sufficient distance from the sides of the vessel to intercept torpedoes and like missiles to prevent them from reaching the hull 60 of a vessel, or causing the torpedoes to explode at a sufficient distance from the hull of the vessel to prevent damage thereto.

The net will be constructed of any suitable material, but will preferably be of steel 65 formed into interlocking links of any desired form and represented conventionally at 10. At its upper edge the net will be coupled to a suitable cable, preferably of steel wire and indicated at 11. The net is main-

tained in position by a plurality of floats or buoys, and the construction of these buoys or floats is the principal feature of the present invention. The floats or buoys may be of any suitable size and of any suitable ma- 70

terial, but will preferably be of relatively light sheet metal cylindrical in transverse section as shown at 12, with pointed or cigar shaped ends 13. The buoys will be ar- 75

ranged in pairs as shown in Figs. 1, 3 and 5 and connected intermediate their ends by 80 a transverse device represented at 14. At their forward ends each pair of the floats is connected by a forwardly pointed or V- shaped member 15 with the center of the 85

member preferably at one side of the medial line between the floats. Each pair of the floats is likewise coupled at their rear ends by a member 16, the latter being arranged obliquely to the longitudinal axis of the 90

floats as shown in Figs. 1 and 3. The member 16 is connected directly to the rear end of one of the floats 12 by a bracket device 17, and connected to the other float by a suitable bracket device 18, the latter being 95 longer than the bracket 17 to support the member 16 in its requisite oblique position. The members 15—16 are in the form of relatively wide plates so that they offer a considerable resistance to the water through 100

which the float device is moved.

As many of the pairs of the float devices as required may be employed, depending upon the length of the vessel with which they are associated, and it is not desired to 105 limit the number of the float devices em- ployed. For the purpose of illustration two of the floats are shown at each side of the vessel, indicated conventionally at 19, and one of the float devices at the rear as shown 110 in Fig. 1. The float devices which are asso- ciated with the sides of the vessel are alike

except that the obliquely directed attachments 15—16 are reversed in position, or so that the shortest portions of the attachments 15 are farthest from the vessel, while 5 the attachments 16 are arranged to incline toward the stern of the vessel, the object to be hereafter explained.

The floats of the device which is located astern of the vessel are coupled at their forward ends by a V-shaped member 20 having its central point in alignment with the medial line between the floats, while the rear or stern portions of the floats are coupled by a similar V-shaped portion 21 likewise 15 with its apex in alignment with a medial line between the floats.

Extending forwardly of the vessel 19 is a boom device 22 rigidly secured to the bow of the vessel and extending in advance of 20 the same. Attached to the members 15 of the forward float device is an eye 23, while a similar eye 24 is located at the forward end of the boom 22. Pull cables 25 are connected respectively to the eyes 23 and 24 as 25 shown in Fig. 1. Eyes 26—27 are connected to the buoy devices from which pull cables 28—29 lead to a winding drum indicated at 30 upon the deck of the vessel. The cables 28—29 are preferably carried over guide- 30 pulleys 31—32 to insure their winding upon the drums. One of the winding devices 30 will be associated with each of the float devices, so that the latter may be drawn toward or permitted to recede from the side of the 35 vessel or at any suitable distance from its stern. By arranging the members 15—16 obliquely to the line of movement of the vessel and holding the float devices coupled to the vessel by the several pull cables, it will 40 be obvious that the longer sides of the members 15 and the members 16 act as sheer blades to hold the float devices in parallel relation to the sides of the vessel, and by shortening or lengthening the pull cables 45 the position of the float devices relative to the vessel may be readily controlled.

The net members 10 are suspended at one end from the member 15 as indicated at 33 and to each of the transverse members 14 of 50 the various float devices as indicated at 34. The net devices are thus maintained in parallel relation to the longitudinal plane of the vessel and medially of the various float devices, and converge to the member 14 of 55 the float device which is located astern of the vessel. The net member is thus supported in position to effectually inclose and guard the hull of the vessel and prevent torpedoes and like missiles from reaching the 60 hull.

The links constituting the net are sufficiently close to prevent the passage of torpedoes and like missiles, and will be as large as possible to reduce the resistance when the 65 net is drawn through the water.

The net hanging loosely from the float devices will yield to the impact of a torpedo and thus serve to check the forward movement of the latter until its force is expended, or the net will serve to explode certain 70 classes of torpedoes when they impact against the net and expend their force a sufficient distance from the hull to prevent damage thereto.

When not required, or when the vessel has 75 passed beyond the danger-zone, the winding devices 30 will be actuated to draw the float devices close to the sides of the vessel upon whose decks the float devices together with the net can be hoisted by suitable windlasses 80 or cranes. Then if the vessel again enters the danger-zone the float devices and net can be quickly disposed in position for defense. Extra nets will be carried to replace those lost or destroyed.

Having thus described the invention, what is claimed as new is:

1. An apparatus of the class described comprising a boom device adapted to be rigidly connected to a vessel and extending 90 in advance of the same, a series of floats arranged in pairs, means for connecting said floats in spaced relation, a net device, means for suspending said net device from the float connecting means and medially of the 95 floats, flexible means connected relatively to said floats and to said boom, and flexible means connected respectively to said floats and to said vessels.

2. An apparatus of the class described 100 comprising a series of floats arranged in pairs, means for connecting said floats in spaced relation, a net device, means for suspending said net device from the float connecting means, sheering members carried 105 by said connected floats and directed obliquely to the longitudinal axes of the floats, and flexible means connected relatively to said floats and adapted to be connected to a vessel.

3. An apparatus of the class described comprising a series of floats arranged in pairs and each pair connected in spaced relation, said pairs of connected floats adapted to be arranged at opposite sides of a vessel, sheering members carried by said connected floats and directed obliquely to the longitudinal axes of the floats, the sheering members being reversely arranged at opposite sides of the vessel, a net device, means 115 for suspending said net devices medially of the floats, and pull cables connected to said floats and adapted to be connected to said vessel.

4. In an apparatus of the class described, 125 a plurality of supporting devices each comprising floats connected together in spaced relation and with sheering members directed obliquely to the longitudinal axes of the floats, said supporting devices adapted to 130

be arranged at opposite sides of and astern of the vessel, a net device suspended from said float devices medially thereof, and pull cables connected to said floats and adapted

5 to be connected to said vessel.

5. An apparatus of the class described comprising a boom device adapted to be rigidly connected to a vessel and extending in advance of the same, a series of floats

10 arranged in pairs, means for connecting said floats in spaced relation, a net device, means

for suspending said net device from the float connecting means and medially of the floats, flexible means connected relatively to said floats and to said boom, flexible means 15 connected respectively to said floats and to said vessel, and sheering members carried by said connected floats and directed obliquely to the longitudinal axes of the floats.

In testimony whereof I affix my signature.

LLOYD JOHNSON. [L. S.]
